STAMP COUNTING MACHINE

Walter Herbert Siinn, London, England, assignor
to R. B. Pullin & Company Limited, Brentford,
Middlesex, England, a British company

Application June 12, 1940, Serial No. 340,204
In Great Britain June 13, 1939

14 Claims. (Cl. 235—98)

This invention aims at providing machines for counting stamps, which term includes any pieces of paper or the like issued in the form of perforated sheets each containing a fixed number of pieces. The machines are required to receive and count sets which vary in shape and in the number of stamps in the set from a complete sheet to a single stamp. To facilitate the description of the invention, it will be assumed that a complete sheet contains sixty stamps, arranged in twelve transverse rows each containing five stamps, but it will be understood that the invention is not limited to machines for use with such sheets. The actual sets may be of any shape; for example a set may consist of eleven stamps arranged in three rows, with four stamps in each of the first two rows and three in the third.

Essentially a machine according to the invention comprises first a series of electrical circuits, each including a relay, equal in number to the maximum number of stamps in a row and a mechanism for so feeding sets of stamps in succession to means for controlling the circuits that each stamp or line of stamps in the set actuates the controlling means and operates a relay. Preferably the controlling means comprise five selector fingers beneath which the sets are fed and which are moved by the sets to control the circuits.

Next, the machine comprises a series of mechanisms, also equal in number to the number of stamps in a row, each controlled by one of the fingers referred to above and actuated in a specific manner each time the relay is operated. Each of these mechanisms serves to count the number of stamps in one of the five lines or columns of the set, and may be called a row-counting mechanism.

Thirdly, the machine comprises means for adding together the numbers of actuations of the row-counting mechanisms, and for registering the result.

Preferably the five row-counting mechanisms are each electrically controlled by parallel circuits which are all controlled by a mechanism that will be called the drive relay and that is operated whenever a row of stamps is passing beneath the selector fingers. Each parallel circuit is also directly controlled by one of the selector fingers, so that its row-counting mechanism will not be actuated unless the corresponding selector finger is moved by a stamp. Thus, if there are five stamps in a row passing beneath the selector fingers, the drive relay will be ac-

tuated once and all five row-counting mechanisms will also be actuated. If, however, only three stamps are passing in a row beneath the selector fingers, two of the parallel circuits will be inoperative, and only three of the row-counting mechanisms will be actuated.

In the preferred machine, the drive relay includes a continuously rotating shaft driven in synchronism with the set-feeding mechanism, and a cam-shaft clutched into engagement with the continuously driven shaft for as long as any selector finger is moved by a stamp. The timing is such that the cam-shaft makes one revolution in the time that it takes a stamp to pass beneath a selector finger, and in each revolution of the cam-shaft a switch in circuit with the five parallel circuits controlling the row-counting mechanisms is actuated by the cam. This arrangement ensures that the total number of actuations of the row-counting mechanisms is equal to the number of stamps.

In order that the invention may be clearly understood and readily carried into effect, a specific example of a stamp counting machine in accordance therewith will now be described with reference to the accompanying drawings, in which:

Figure 1 is an elevation of the mechanism by which the sheets or sets of stamps are fed through the machine;

Figure 2 is a plan of the arrangement shown in Figure 1;

Figure 3 is a section on the line III—III in Figure 1;

Figure 4 is a section on the line IV—IV in Figure 1;

Figure 21 is a plan view of the machine shown in Figure 20; and

Figure 22 is a diagram of the electrical connections.

The stamp-feeding mechanism shown in Figures 1 to 4 includes a supporting plate 1, in which are journalled four pulleys, 2, 3, 4 and 5 with a pair of endless belts 6 and 7 passing respectively around the pulleys 2, 3 and 4, 5. The pulleys 2 and 5 are coupled together by a pair of spur gears 8 and 9, as shown in Figure 3, so that when the pulleys are driven there is no slip between the two belts. The latter are positively driven at a constant speed, in a manner described below, and the contiguous runs of the two belts are forced to move in a curved path by the provisions of a curved guide plate 10 secured to the supporting plate 1. Thus, the upper run of the belt 7 rests on the curved guide plate 10 and is pressed into firm contact with the lower run of the belt 6. The firm engagement between the two belts is ensured by the provision of flanged jockey pulleys 11 and 12 mounted respectively on bell-cranks 13 and 14 which are pivoted to the supporting plate 1 and are acted upon by tension springs 15 and 16. In this way the jockey pulleys are urged outwardly and so maintain their associated belts taut, ensuring that the co-operating runs of the belts remain pressed firmly together.

The belt pulleys, 2, 3, 4 and 5 rotate in the direction of the curved arrows shown in Figure 1, so that the contiguous runs of the two belts travel from left to right. A sheet or set of stamps 17 is fed by hand into a slot 17a at the left-hand end of the mechanism and is correctly positioned by sliding it laterally until it encounters a guide plate 17b. The latter is so arranged that approximately half the width of the innermost line of stamps is gripped between the contiguous runs of the endless belts, and in this way the set of stamps 17 is fed from left to right through the mechanism. The set of stamps is supported and prevented from sagging by passing over a table 18 indicated in Figure 2.

The stamp-feeding arrangement described above supplies the set of stamps 17 to the mechanism shown in Figures 5 to 7. This mechanism includes a roller 19 journalled horizontally in a supporting bracket 20, and vertically above this roller there are five narrow rollers 21-25, which are arranged to rotate as a unit and are coupled to the lower roller 19 by gearing 26 so that when

a drive is transmitted to a sprocket 27 on the shaft of the lower roller, the latter and the co-operating narrow rollers rotate in the respective directions indicated by the curved arrows in Figure 5. Each of the five rollers 21-25 is provided with peripheral teeth 28 at intervals, serving to cancel or deface the stamps as they pass through the mechanism. The lower roller 19 is formed with five grooves 29 to receive the teeth 28 of the narrow rollers.

Five selector fingers 30 are accommodated in the gaps between the narrow rollers 21-25, and are pivoted on a rod 31 extending parallel to the axes of the rollers. These selector fingers, which are all identical, are each formed with a downwardly extending pointed projection 32 (Figure 5), and each finger is arranged so that its projection 32 just makes contact with the surface of the roller 19. When the sheet of stamps is fed between the rollers as indicated in Figures 5 and 6, the leading edge of the first stamp in any line is caused to pass between the roller 19 and the corresponding projection 32 of the selector finger concerned, and as a result this lever is tilted slightly. This very slight tilting movement is magnified by causing the selector finger 30 to produce upward movement of a rod 33 by which the movement is communicated to a further lever 34 pivoted at 35. The free end of the lever 34 is fitted with an abutment stud 36 provided with an adjustment screw 37, and also carries a counter-weight 37a. Two sets of spring-set contacts 38a-38e and 39a-39e, the function of which will be described below, are interconnected by a member 40 so that they are operated simultaneously when the associated abutment stud 36 is moved upwardly by the lever system.

In order to provide for different ratios in the lever system, the selector finger 30 and the associated lever 34 are provided with holes 41 at various distances from the fulcrums of the levers, so that the leverage may readily be altered by inserting the pointed ends of the rod 33 in different sets of holes. The rod 33 is arranged to pass with adequate clearance through an opening 42 in a stationary plate 43 at one end of which there is an adjustable pin 44 acting as a guide for the end of the selector finger 30.

It will be seen from Figure 6 that there are five sets of the spring-set contacts 38a-38e and 39a-39e, each set being associated with one of the selector fingers 30 and each actuated by its own lever system, and abutment stud 36. It will be appreciated that the arrangement is such that so long as there are stamps in the sheet 17 passing between one of the projections 32 and the roller 19, the corresponding selector finger 30 is tilted and, in the way already described, the associated pairs of spring-sets are closed, and as a result the stamps are counted in a manner which will be described below. Whenever a gap occurs in any of the rows of the sheet of stamps, due to one or more stamps having been removed from that row, the selector finger 30 appertaining to the row in question reverts to its inoperative position, in which the associated spring-sets are open, and when this is the case, the machine ceases counting stamps for the particular part of the row in question.

The mechanism shown in Figures 8 to 10 constitutes what is conveniently referred to as the drive relay. It includes a continuously rotating shaft 45 journalled in a supporting bracket 46 and provided at one end with one half of

a dog-clutch 47. The other half of this clutch is carried on an axially slidable cam-shaft 48 to which a cam 49 is keyed. The cam-shaft 48 is journalled in ball-bearings 50 and is cupped at each end to receive thrust balls 51 and 52 respectively. The end of the shaft with the ball 51 extends within the shaft 45 which is made hollow and contains a block 53 which is urged into contact with the ball 51 by means of a spring 54 which is accommodated in the hollow shaft and bears at its other end against an adjustment screw 55. The result is that the action of the spring 54 tends to keep the two halves of the clutch 47 separated so that the drive of the shaft 45 is not transmitted to the cam-shaft 48.

The ball 52 at the other end of the cam-shaft bears against an arm 56 which is pivoted at 57 and carries the armature 58 of a solenoid 59 constituting the actuating relay. When the latter is energised, and attracts its armature 58, the pivoted lever 56 is correspondingly deflected and slides the cam-shaft 48 axially so as to cause the two halves of the dog-clutch 47 to engage, thus causing the cam 49 to be rotated. When the relay is de-energised, the lever 56 is restored to its initial position by the tension of a spring 60, and this enables the spring 54 to push the cam-shaft back to its original position in which the clutch 47 is disengaged.

The continuously rotating shaft 45 is driven in synchronism with the stamp-feeding mechanism shown in Figures 1 to 4 and the arrangement is such that each time one of the selector fingers 30 (Figures 5 to 7) is engaged by a stamp, the closing of those of the spring-sets 38a-38e and 39a-39e concerned results in the drive relay 59 being energised, whereupon the cam 49 is rotated in the way already described. This cam continues to rotate for as long as any selector finger is actuated by a stamp, and the timing is such that the cam-shaft 48 makes one revolution in the time that it takes a stamp to pass beneath the projection 32 of the corresponding selector finger 30, and in each revolution of the cam-shaft a spring-set 51 is closed by the cam. This spring-set 51 is in circuit with the spring-sets 39a-39e (Figure 5) associated with the selector fingers 30. The way in which these circuits function will be described below.

In order to prevent the accumulation of small errors, provision is made, after each actuation of the drive relay 59, for restoring the cam-shaft 48 to a definite zero position every time the relay is de-energised. This is achieved by providing a radial tongue 62 on a disc 63 which is secured to the cam-shaft 48, the tongue in question being arranged to co-operate with a correspondingly shaped slot 64 formed in a pedestal 65. The result is that once the cam-shaft 48 has commenced to rotate, owing to the clutch 47 being engaged, it must always carry out a complete revolution because, as is clearly shown in Figure 10, whenever the clutch 47 is engaged and the cam-shaft 48 commences to rotate, the tongue 62 (which has been shifted axially out of the slot 64 by the sliding movement of the cam-shaft) bears against the surface of the pedestal 65 and consequently must remain in this condition until it again comes into registration with the slot 64. Then, if the drive relay 59 has become de-energised in the meantime, the spring 54 acts to shift the cam-shaft 48 axially in the way already described, this sliding movement being permitted by the fact that the tongue 62 can now enter the slot 64. It follows that so long as the drive re-

lay remains de-energised, the cam-shaft is maintained in a definite zero position, since it is locked by the tongue 62 engaging with the slot 64.

5 Owing to the fact that the teeth of the clutch 47 disengage gradually, and not instantaneously, when the tongue 62 enters into registration with the slot 64 after completing a revolution, there is a tendency for the tongue to continue 10 its turning movement in the slot until the clutch has become fully disengaged. In order to allow for this, the wall of the slot which is approached by the turning tongue is constituted by a blade spring 64a which yields under the lateral force 15 exerted by the tongue during the time required for complete disengagement of the clutch 47. As an additional safeguard, a further blade spring 64b is arranged as shown. It will be appreciated that as soon as the opposing teeth of the clutch 20 are completely clear of each other, the springs 64a and 64b revert to their undeflected condition and consequently the tongue 62, and with it the cam-shaft 48, is restored to a definite zero position.

25 It may be mentioned here that the total number of stamps in any sheet or set which is passed through the machine is enumerated by means of a supply of balls, each of which represents one stamp. Every time that a stamp comes into engagement with the projection 32 of one of the selector fingers 30 (Figure 5), one of the aforesaid balls is automatically supplied from a storage hopper to an automatic counting device. The release of the balls is effected by means of devices which may conveniently be termed "ball-dropping relays." Five of these are employed in the present example, there being one such relay associated with each of the five selector fingers. That is to say, each ball-dropping relay is energised each time that a stamp passes beneath the projection of its associated selector finger, and consequently each of these relays governs the counting of the stamps located in the line with which it is associated.

30 45 One of the five ball-dropping relays is illustrated in Figures 11 and 12. It is provided with a ball-chute 66 consisting of a hollow vertical cylinder, into which the balls 67 are supplied from a ball-storage hopper, which is shown in 50 Figures 13 to 15. The internal diameter of the ball-chute 66 is only slightly larger than the diameter of the balls, so that the latter rest on top of each other in the chute, as indicated in Figure 12. The lowermost ball at any time is embraced by a crutch 68, formed with three depending arms 69. This crutch is carried at one end of a lever 70 which is pivoted at 71 and carries the armature 72 of the actuating relay 73. So long as the relay 73 remains de-energised, the crutch is maintained in the position indicated 55 in full lines in Figure 11 by means of a laminated spring 74 acting upon the lever 70, and in this condition the lowermost ball in the chute 66 is embraced by the arms of the crutch, and this state of affairs persists until the relay 73 is energised. When this happens, owing to the attraction of the armature 72, the crutch 68 is moved into the position shown in dotted lines in Figure 11 and as a result the ball which is embraced by the crutch is brought into registration with a discharge opening 75 through which it falls into the apparatus shown in Figures 17 to 19, by means of which the balls are counted. The opening 75 is formed in a block 76, and as 60 65 70 75 will be understood from what has already been

said, its mouth is out of registration with the lower end of the ball-chute 66, the amount by which these two openings are out of registration being represented, of course, by the lateral movement of the crutch.

When one of the balls 67 has been dropped through the opening 75, the succeeding ball first of all rests on one of the lateral arms of the crutch, so that when the latter is returned upon de-energisation of the relay 73, the ball in question rolls into the crutch, and so is ready to be dropped through the opening 75 when the crutch is next displaced. When the crutch is in the position shown in full lines in Figure 11, the ball which it embraces rests on a ledge 77 of the block 76.

The storage hopper from which the balls 67 are supplied to the chutes 66 of the five ball-dropping pin relays is shown in Figures 13 to 15. This hopper comprises a box-like structure 78 the bottom of which is provided with five tubular outlets 79, each of which is connected to one of the ball-chutes 66 (Figure 12) of the five ball-dropping relays. The lower part of the hopper 78 contains a horizontal roller 80 which is rotated through gearing 81. A sloping metal plate 82 is arranged as shown in Figure 15 and some of the balls (not shown) in the hopper roll off this plate onto the roller 80. It will be appreciated that the remaining balls will already be resting on the surface of the roller 80. The interior of the hopper 78 is also fitted with a series of curved guides 83 which serve to guide the balls into the respective outlets 79. Moreover, in order to prevent the balls from becoming jammed, they are continuously agitated by providing the roller 80 with a number of spring-pressed triggers 84. As shown in Figure 16, these triggers 84 are carried on three rods 85 extending axially through the roller 80, which is made hollow. The triggers project through slots 86 in the surface of the roller and each trigger is acted upon by a coiled spring 87 so that it normally maintains the position indicated in Figure 15. The roller 80 is rotated in the direction of the curved arrow in Figure 15 and the triggers 84 pass through slots 88 provided in the plate 82. The triggers do not pass centrally through the passages defined by the guides 83, but along one side of these passages, as will be clear from Figure 14. As a result, when the roller 80 rotates, the triggers 84 keep the balls in a state of agitation and so prevent them from becoming jammed in any way in the entrances to the outlets 79. However, should any of the triggers 84 experience undue resistance to its movement, the associated spring 87 yields and the trigger in question can move back through its slot 86 in the roller 80 until it is again restored to its normal position when it has parted company with the balls.

As already mentioned above, the balls which are released by the ball-dropping relays are supplied to the apparatus shown in Figures 17 to 19. This constitutes a ball-counter-operating mechanism and also a ball pump in that it pumps the balls 67 back to the ball-storage hopper after they have been automatically counted. The balls collect in a hopper 90 at the top of this mechanism. As shown in Figure 19, the hopper has a sloping bottom from which the balls fall into a narrow channel 91 of rectangular cross-section containing a toothed wheel 92 which is very similar to a bicycle sprocket and constitutes the pump wheel of the ball pump. This pump wheel is driven through a spring-loaded fibre-faced

friction clutch 93 (Figure 18) from a shaft 94 (Figure 18) which is continuously driven through gearing 95 so long as the machine is in operation. The pump wheel is mounted on a co-axial shaft 96, and the clutch spring 97 which surrounds this shaft is adjusted by means of nuts 98. The provision of the spring-loaded clutch serves as a safeguard in case a ball should jam anywhere between the pump wheel and the stationary parts of the apparatus, because in that event the clutch would slip and so obviate damage to the ball pump.

The width of the channel 91 is such that only one ball at a time can drop on to the pump wheel 92 and enter the gap between two successive teeth, as indicated in Figure 17. In order to obviate the risk of the balls becoming jammed across the upper end of the channel 91, a vertically reciprocating plate 99 is arranged to extend along one side of the channel and to project into the base of the hopper 90 as shown in Figure 19. This plate 99, which is reciprocated by an eccentric 100 on the shaft of the pump wheel, serves to break up any formation of the balls which might lead to jamming, as will readily be understood from Figure 19. Moreover, a continuously revolving horizontal roller 101 driven from the shaft 94 through gearing 102 is positioned, as shown in Figure 17, at the upper end of the channel 91 so that it is just clear of the teeth of the pump wheel. The purpose of this roller is to roll any ball that may be tending to jam into a vacant tooth space.

The pump wheel, which rotates in the direction of the curved arrow in Figure 17, serves to space out the balls at equal intervals and carries them around against a curved guide 103 which may be regarded as constituting an extension of the channel 91. It will be noticed that the roller 101 is located adjacent the leading edge 103a of the guide 103, i. e. slightly in advance of the point at which the teeth of the pump wheel enter the space bounded by the guide 103. As a result, if a ball should jam between the roller 101 and one of the approaching teeth, the clutch 93 momentarily slips whilst the roller rolls the ball into a vacant tooth space.

As can be seen from Figures 18 and 19 the balls 67 project from both sides of the teeth of the pump wheel but from one side more than the other, owing to the wheel being located nearer one side of the channel. The consequence of this is that as each ball, in turn, is carried past the end of a spring-pressed plunger 104 which projects slightly into the path of travel of the balls, the plunger is forced outwardly against its spring-set 105 to energise the circuit of an electromagnetic counter. That is to say, each stamp that passes through the machine results in one of the balls 67 registering its presence electrically in the way described.

After each ball has actuated the plunger 104 it is forwarded by the pump wheel to the lower end of a vertical tube 106 the side of which adjacent the pump wheel is formed with a vertical slot to receive the teeth of the pump wheel. Thus, the teeth enter the lower end of the slot at 107 (Figure 17) and carry the balls upwardly inside the tube 106 until each tooth, in turn, moves out of the upper end of the slot leaving the corresponding ball inside the tube. The first ball to be left in the tube in this way drops down on to the next ball which is still being carried upwardly by the pump wheel. When this second ball is freed

from the pump wheel the two balls rest on the next ball which is being carried upwardly by the pump wheel. The consequence is that a column of the balls is gradually pumped up the tube 106 which leads into the ball-storage hopper 78 shown in Figures 13 to 15.

The arrangement of the complete machine is indicated in Figures 20 and 21, which represent respectively a side elevation and plan. The drive for the various components is derived from an electric motor 108 through a gear-box 109, a chain and sprocket drive 110 being taken to a lay-shaft 111 from which the pulley 5 (Figure 1) is driven directly through a dog-clutch. The latter is constituted by a pair of pins (not shown) on the end of the lay-shaft engaging in slots 112 and 113 (Figure 1) formed in the hub of the pulley 5.

The superposed rollers (see also Figures 5 to 7) between which the sheet of stamps 17 is fed, are driven from the lay-shaft 111 by means of a chain 142, and similarly a chain 143 drives the sprocket 95 (see also Figure 18) of the ball pump P. The latter is connected by the tube 106 to the ball-storage hopper 78 (see also Figures 13 to 15). The five ball-dropping relays (see also Figures 11 and 12) are indicated at R₁-R₅, and it will be seen from Figure 20 that they are located below the ball-storage hopper 78 and above the hopper 90 of the ball pump.

Referring to the circuit diagram of Figure 22, the motor 108 is energised from a current supply S. The five spring sets 38a-38e (see also Figures 5 and 6) are connected in parallel with one another and also in parallel with the winding of a delayed action relay 114 which, for convenience, is termed the "slugging relay." This relay 114 controls the drive relay 59 by actuating its contact 115 which are opened when the slugging relay 114 is energised but fall back and close when the relay 114 is deenergised. In other words, the de-energising of the slugging relay 114 energises the drive relay 59 from the positive line S₁, conductor 119, contacts 115, relay 59, to the negative line S₂. Also, a resistor 116 is connected in shunt with a pair of contacts 117 in the circuit of the slugging relay 114, which circuit runs from the positive line S₁, conductor 119, contacts 117, relay winding 114, conductor 120, to the negative line S₂. The contacts 117 are also opened when relay 114 is energised, and then include the resistor 116 in the circuit of said relay for the purpose of reducing the current holding the relay 114 in the on position after it has operated, and thereby increasing the speed of break of relay 114 owing to the consequent reduction of the time needed for its flux to collapse.

The slugging relay 114 is provided to take account of the fact that what may be termed the electrical length of a stamp is somewhat greater than its actual physical length. This arises from the fact that when the leading edge of a stamp reaches the pointed projection 32 (Figure 5) of one of the selector fingers 30, the selector finger in question commences to rock before the leading edge of the stamp arrives at the actual point of the projection. In fact, the rocking movement is initiated when the leading edge of the stamp strikes the inclined surface of the projection 32. However, the selector finger does not return to its initial position until the actual point of the projection 32 is cleared by the trailing edge of the stamp. In short, the slugging relay 114 has the effect of reducing the electrical length of a stamp

to its physical length and also ensures that the drive relay 59 is only energised once for each stamp that passes. The spring sets 39a-39e are connected as shown, in parallel between the conductor 119 and the respective ball-dropping relays R₁-R₅ which are, therefore, connected in parallel between the positive line S₁ and the negative line S₂ through the spring set 61 (see also Figure 8). The latter, as already described is controlled by the cam 49 which is actuated under the control of the drive relay 59.

Assuming that a stamp passes beneath the projection 32 of the selector finger 30 (Figure 5) associated with the spring-sets 38a and 39a, both of these are closed and the spring set 38a short-circuits the relay 114. As a result, the slugging relay 114 is de-energised and the drive relay 59 energised whereupon it causes the cam 49 to be rotated to close the spring-set 61, thus completing the circuit through the ball-dropping relay R₁ which is associated with the closed spring-set 39a. The ball which is released, in the way described earlier, closes the spring-set 105 (see also Figures 17 and 18) which energises an electromagnetic counter 118. The latter is preferably arranged to register the cash value of the stamps passing through the machine.

If there are five stamps in the transverse row passing the selector fingers at any given time, the drive relay receives one energisation but all the five ball-dropping relays R₁-R₅ are now energised, so that five balls are released and proceed to the counting mechanism and ball-pump.

It has already been stated that every time a stamp comes into engagement with the projection 32 of one of the selector fingers 30 (Figure 5), one of the balls is automatically supplied from the storage hopper 78 to the automatic counter operating device 104, 105. Indeed, when the projection 32 encounters the first stamp of a longitudinal line, it is actuated to close a spring set, for instance, 38a, 39a, but if the next stamp in the longitudinal line follows immediately after the first stamp and there is not a gap or interval, the dog clutch 47 is kept in engagement because the drive relay 59 is kept energised owing to the fact that the slugging relay 114 is kept short-circuited by the spring set 38a. In other words, at the end of the first stamp, when the tongue 62 registers with the slot 64, it is prevented from dropping into the slot and passes on for a second revolution. This is continued until the end of the longitudinal line of stamps is reached, or until a stamp in the line is missing. The spring set 39a in circuit with the ball-dropping relay R₁ is kept closed during all this time, but the circuit of the relay R₁ is opened and completed in each revolution of the shaft 48 by means of the cam 49, so that the relay R₁ drops one ball during each revolution, that is for each stamp in the line. In this way, a ball is dropped by one or other of the relays R₁ to R₅ for each stamp in each of the longitudinal lines, and the counter operating device 104, 105 is actuated a number of times equal to the total number of stamps in a sheet.

It may be mentioned in conclusion that both the drive relay 59 (Figures 8 and 9) and the ball pump shown in Figures 17 and 18 constitute self-contained units which may well be employed for other purposes having no connection with stamp-counting machines but for which their respective functions are of service. Thus, the drive relay could be used for any purpose requiring a shaft to make one revolution for each energisation of the

relay. Similarly, the ball pump may be used for any purpose requiring balls to be pumped in a stream from one point to another.

I claim:

1. A mechanism for counting stamps in complete or partial sheet form, comprising, in combination, means for feeding the sheet into the machine, a plurality of electrical circuits equal in number to the maximum number of stamps in a transverse row in any of said sheets, a corresponding number of selector fingers for controlling said circuits pivoted on a horizontal axis, a roller disposed below said selector fingers, a downwardly extending pointed projection on the underside of each of said selector fingers normally just contacting the surface of said roller, said sheet-feeding means conveying the stamps between said roller and said pointed projections to cause rocking of said selector fingers for each line of stamps, electrical contacts associated with said selector fingers, a system of multiplying levers for actuating the contacts associated with each of said selector fingers, means for transmitting the rocking movement of each of said selector fingers to the corresponding system of multiplying levers, a counter, and counter operating means controlled by said contacts.

2. A mechanism for counting stamps in complete or partial sheet form, comprising, in combination, means for feeding the sheets into the machine, a source of electrical supply, a plurality of electrical circuits equal in number to the maximum number of stamps in a transverse row in any of said sheets, means for controlling said circuits, said circuit-controlling means being selectively operable by the stamps fed thereto, a hopper containing balls, a continuously rotating roller in the lower part of said hopper, said lower part being formed with discharge outlets, a series of curved guides leading to said discharge outlets, resiliently mounted radial projections on said roller positioned to move upwards along one side of said curved guides to prevent jamming of said balls, means operative to release one ball from said hopper for each actuation of said circuit-controlling means, and means for enumerating the total number of balls released from said hopper.

3. A machine as claimed in claim 2, wherein said roller is formed with slots, and said radial projections are constituted by spring-pressed triggers any of which recedes into the associated one of said slots in the event of undue resistance being encountered.

4. A mechanism for counting stamps in complete or partial sheet form, comprising, in combination, means for feeding the sheets into the machine, a source of electrical supply, a plurality of electrical circuits equal in number to the maximum number of stamps in a transverse row in any of said sheets, means for controlling said circuits, said circuit-controlling means being selectively operable by the stamps fed thereto, a container for balls, means responsive to the operation of said circuit-controlling means to release one ball from said container for each stamp fed through the machine, a hopper to receive the balls so released, a casing beneath said hopper, said casing being formed with a narrow channel, a frictionally-driven sprocket wheel mounted in said channel so that balls from said hopper enter the spaces between the teeth of said sprocket wheel, a spring-pressed plunger disposed in said narrow channel to project slightly in the path of travel of the balls carried by said sprocket wheel, switch

contacts operable by said spring-pressed plunger, and electromagnetic counter operating means controlled by said switch contacts, and a plate adapted to reciprocate in said channel to prevent balls jamming in the mouth of said channel.

5. A mechanism for counting stamps in complete or partial sheet form, comprising, in combination, means for feeding the sheets into the machine, a source of electrical supply, a plurality of electrical circuits equal in number to the maximum number of stamps in a row of any of said sets, means for controlling said circuits, said circuit-controlling means being selectively operable by the stamps fed thereto, a container for balls, means responsive to the operation of said circuit-controlling means to release one ball from said container for each stamp fed through the machine, a hopper to receive the balls so released, a casing beneath said hopper, said casing being formed with a narrow channel, a frictionally-driven sprocket wheel mounted in said channel so that balls from said hopper enter the spaces between the teeth of said sprocket wheel, a curved wall forming part of said casing, a roller mounted at the upper end of said channel just clear of the teeth of said sprocket wheel and slightly in advance of the point at which said teeth enter the space bounded by said curved wall, means for continuously rotating said roller, a spring-pressed plunger disposed in said narrow channel to project slightly in the path of travel of the balls carried by said sprocket wheel, switch contacts operable by said spring-pressed plunger, and electromagnetic counter operating means controlled by said switch contacts.

6. A mechanism for counting stamps in complete or partial sheet form, comprising, in combination, means for feeding the sheets into the machine, a source of electrical supply, a plurality of electrical circuits equal in number to the maximum number of stamps in a row of any of said sets, means for controlling said circuits, said circuit-controlling means being selectively operable by the stamps fed thereto, a container for balls, means responsive to the operation of said circuit-controlling means to release one ball from said container for each stamp fed through the machine, a hopper to receive the balls so released, a casing beneath said hopper, said casing being formed with a narrow channel, a frictionally-driven sprocket wheel mounted in said channel so that balls from said hopper enter the spaces between the teeth of said sprocket wheel, a curved wall forming part of said casing and constituting a retaining means for the balls carried by said sprocket wheel; said casing having a tube which adjoins the exit end of said curved wall and communicates with said ball container, the side of said tube which faces said sprocket wheel being formed with a longitudinal slot to receive the teeth of said wheel, whereby the balls forwarded by said wheel are propelled along said tube, being retained therein when said wheel teeth pass out of said slot; a counter and means for operating said counter, said last mentioned means being operable by the balls forwarded by said sprocket wheel.

7. A machine for counting stamps in sets of perforated sheet form, comprising, in combination, for feeding sheets longitudinally, a source of electrical supply, a plurality of electrical circuits equal in number to the maximum number of stamps in a row of any of said sets, means for controlling said circuits, said circuit-controlling

means being selectively operable by the stamps fed thereto, a container for balls, means responsive to the operation of said circuit-controlling means to release one ball from said container for each stamp fed through the machine, a hopper to receive the balls so released, a casing beneath said hopper, said casing being formed with a narrow channel, a frictionally-driven sprocket wheel mounted in said channel so that balls from said hopper enter the spaces between the teeth of said sprocket wheel, a reciprocatable plate mounted to extend along one side of said channel and into the base of said hopper, means for reciprocating said plate to break up any formation of said balls that might lead to jamming, a counter and means for operating said counter, said last mentioned means being operable by the balls forwarded by said sprocket wheel.

8. An apparatus for propelling a stream of balls from one point to another, comprising a container for said balls, a casing disposed beneath said container, said casing being formed with a narrow channel, a frictionally-driven sprocket wheel mounted in said channel so that balls from said container enter the spaces between the teeth of said sprocket wheel, a curved guide forming part of said casing, and acting as a retaining means for the balls carried by said sprocket wheel, a roller mounted at the upper end of said channel just clear of said teeth and slightly in advance of the point at which said teeth enter the space bounded by said curved guide, and means for continuously rotating said roller, said casing having a tube extending upwardly therein which adjoins the exit end of said curved guide, the side of said tube which faces said sprocket wheel being formed with a longitudinal slot to receive the teeth of said wheel; whereby the balls forwarded by said wheel are propelled along said tube, being retained therein when said teeth emerge from said slot.

9. A machine for counting stamps in a sheet composed of a plurality of parallel longitudinal lines of stamps, the machine comprising, in combination, feelers allocated respectively to said lines, means for feeding said sheet past said feelers in the direction of said longitudinal lines, a counter and counter actuating mechanism adapted to undergo cyclic motion, operating means for said counter actuating mechanism responsive to the passage of a sheet past said feelers whereby said counter actuating mechanism undergoes cyclic motion so long as a stamp in the sheet is passing any one of said feelers, ball-dropping counting devices allocated to said feelers and actuated to release counter balls at a rate determined by said counter actuating mechanism, said feelers determining the number of balls released in each cyclic movement of said actuating mechanism, and means for driving said feeding means at a rate equal to the rate at which said counter actuating mechanism undergoes cyclic movement.

10. A machine for counting stamps in a sheet composed of a plurality of longitudinal lines of stamps, adjacent stamps in different lines thereof composing transverse rows of stamps, the machine comprising, in combination, sensing means adapted to engage the sheet, means for feeding said sheet past said sensing means in the direction of the longitudinal lines of stamps whereby said sensing means engages successively the transverse rows of stamps and the stamps in each transverse row simultaneously, a counter and counter actu-

ating devices allocated respectively to the longitudinal lines in the widest sheet that the machine is designed to accommodate, actuating mechanism for said counter actuating devices, said 5 actuating mechanism being operative simultaneously to actuate a group of said counter actuating devices selected according to the number of stamps in a transverse row thereof passing said sensing means and to actuate said selected groups 10 in succession at a rate corresponding to the rate at which said transverse rows pass said sensing means and storage means interposed between said counter actuating devices and said counter whereby said counter may continue to count the stamps 15 in a transverse row thereof after the actuation of a group of said counter actuating devices as a result of the action of the row of stamps on said sensing means.

11. A machine for counting stamps in a sheet 20 composed of a plurality of parallel longitudinal lines of stamps, the machine comprising, in combination, feelers allocated respectively to said lines, means for feeding said sheet past said feelers, counting devices allocated respectively to said 25 feelers and including electromagnets, sets of contacts respectively operated by said feelers and connected respectively to said electromagnets, further contacts to which said electromagnets are connected in parallel, a counter and counter actuating mechanism, electrically controlled means for driving said counter actuating mechanism cyclically, said electrically controlled means being rendered operative through said sets of contacts to cause said counter actuating mechanism to 30 undergo cyclic movement whenever a stamp is in engagement with any of said feelers, and means for driving said feeding means such that stamps pass said feelers at a rate equal to the rate at which said counter actuating mechanism undergoes 35 cyclic movements, said counter actuating mechanism closing said further contacts in each cyclic movement and thereby completing circuit through such of said counting devices as are in circuit with contacts, in said sets of contacts, 40 closed by said feelers.

12. A machine for counting stamps in a sheet composed of a plurality of longitudinal lines of stamps, adjacent stamps in different lines thereof composing transverse rows of stamps, the machine comprising, in combination, feelers allocated respectively to the longitudinal lines in the widest sheet that the machine is designed to accommodate, means for feeding said sheet past said feelers in the direction of the longitudinal 55 lines of stamps whereby said feelers engage successively the transverse rows of stamps and the stamps in each transverse row simultaneously, a counter operable by tokens, means for feeding said tokens successively through operative relationship with such counter, token delivery devices allocated respectively to said feelers and operative to deliver tokens to said token feeding means, means for actuating said token delivery devices selectively operable by said feelers, said 60 actuating means including a member adapted to undergo cyclic movement while any one of said feelers is in engagement with a stamp, and also including elements adapted whenever said last-mentioned member is undergoing cyclic movement to operate said token delivery devices simultaneously in groups respectively corresponding to the number of stamps in successive rows thereof passing said feelers.

13. A machine for counting stamps in a sheet 75 composed of a plurality of longitudinal lines of

stamps, adjacent stamps in different lines thereof composing transverse rows of stamps, the machine comprising, in combination, a plurality of feelers allocated respectively to the longitudinal lines in the widest sheet that the machine is designed to accommodate, electric switches allocated respectively to said feelers to be operated selectively as stamps are fed past said feelers, means for feeding a sheet of stamps past said feelers in the direction of the longitudinal lines of stamps whereby the transverse rows of stamps pass said feelers in succession so that said switches are operated in groups respectively corresponding to the number of stamps in the successive transverse rows thereof, token delivery devices allocated respectively to said switches, electric operating units for said token delivery devices connected respectively to said switches, a switch common to said operating units, electrically operable means for closing said common switch periodically at a rate corresponding to the rate at which the transverse rows of stamps pass said feelers, electrical control means interposed between said first-mentioned switches and said means for operating said common switch whereby said common switch is closed periodically so long as any of the feelers is in engagement with a stamp in a passing sheet, and counter mechanism operable in succession by tokens delivered by said token delivery devices.

14. A machine for counting stamps in a sheet composed of a plurality of longitudinal lines of stamps, adjacent stamps in different lines thereof composing transverse rows of stamps, the machine comprising, in combination, a plurality of feelers allocated respectively to the longitudinal lines in the widest sheet that the machine is designed to accommodate, means for feeding said sheet in the direction of said longitudinal lines past said feelers, switches operable by and allocated respectively to said feelers, electrically operable counter actuating devices connected respectively to said switches, a master electric switch to which the counter actuating devices are connected in parallel so that each said counter actuating device is operable only when said master switch is operated as well as the associated feeler operated switch, means for operating periodically said master switch at a rate corresponding to the rate at which transverse rows of stamps pass said feelers, electrical means for maintaining the operation of said master switch operating means, said electrical means being controlled by said feelers whereby said periodic operation continues so long as a feeler is in engagement with a stamp in a sheet, and a common counter operable by said counter actuating devices.

WALTER HERBERT SLINN.
